UNITED STATES PATENT OFFICE.

ROBERT FRANCIS ARMSTRONG, OF LA CYGNE, KANSAS.

ARTIFICIAL HAND.

1,334,689.

Specification of Letters Patent. Patented Mar. 23, 1920.

Application filed October 27, 1919. Serial No. 333,710.

To all whom it may concern:

Be it known that I, ROBERT F. ARMSTRONG, a citizen of the United States, and a resident of La Cygne, in the county of 5 Linn and State of Kansas, have made certain new and useful Improvements in Artificial Hands, of which the following is a specification.

My invention relates to artificial body 10 members, and more particularly to an improved artificial hand.

An important object of my invention is to provide an artificial hand capable of performing all of the important functions of 15 a human hand.

Another important object of my invention is to provide an improved artificial hand of simple durable construction, reliable in operation and easy and inexpensive 20 to manufacture.

Other object and advantages reside in certain novel features of construction, arrangement and combination of parts and will become more apparent as the description 25 proceeds, reference being had to the accompanying drawings forming a part of this specification, and in which;

Figure 1 is a perspective view showing the hand in position assumed when employed to carry baggage, buckets, or the like.

Fig. 2 is a perspective view showing parts of the hand about to assume position whereby the index and middle fingers may be 35 utilized as a hook.

Referring to the drawings it will be seen the hand member proper indicated generally at A is hollow and preferably formed of pressed steel or aluminum. It may be 40 connected to the wrist member (not shown) by any conventional means, such for instance, as a plate B and threaded stud C. The hand member proper is of course formed and shaped to approximate the appearance of the human hand.

Integral or otherwise rigidly formed with the hand member proper is a middle finger member 5. The hand proper is provided adjacent the middle finger member with an 45 opening adapted to accommodate the inner flattened portion 6 of the index finger member 7. The inner portion of the index finger member is mounted upon a pivot 8, the axis of which extends perpendicularly through 50 the hand from the palm to the back thereof. The pivot, as well as the formation of the

opening in the hand prevent any motion of the index finger member except a swinging motion toward and away from the middle finger about the axis of the pivot 8 as 60 defined.

A blade spring 9 is adapted to normally urge the index finger member to bear against the middle finger member and for this purpose it is bowed as shown in Fig. 65 2, and has one end secured to the interior wall of the hand proper by means of rivets or the like 10, and has its other end provided with a stud 11 seated in a recess provided therefor in the adjacent inner portion 70 of the index finger member. For operating the index finger member to cause the same to swing away from the middle finger member against the action of the spring 9, a cord 12 is provided which is attached to the index 75 finger member as shown in the drawings, and is itself connected to and actuated by the body harness usually provided (not shown).

A thumb member is provided and is arranged with respect to the hand member to approximate the arrangement of the human thumb to the human hand in all respects. It is to be noted that all of the finger members heretofore described and to be herein- 80 after described are arranged in this manner. The first phalanx 13 has a flattened inner portion 14 extending into the interior of the hand, and this phalanx is constrained to swing on a pivot 15 having its axis sub- 85 substantially parallel to the pivot 8 so that the motion of swing is transversely or approxi- mately transversely to the plane of the palm of the hand. The outer phalanx 16 is joined to the inner phalanx by a pivot 17. The 90 inner and outer phalanges are connected together by an interfitting tongue and groove structure indicated by 18 and 19, respectively. Shoulders 20 formed on the inner phalanx and shoulders 21 formed on the outer phalanx are adapted to abut when 95 the outer phalanx has been swung a certain distance with respect to the inner phalanx to limit the distance or amount of this relative swing in one direction.

A blade spring 22 has one end secured to the interior wall of the hand proper and is flexed so that its other end bears against the inner portion 14 of the phalanx 13, whereby the spring 22 is normally under 100 tension and tends to swing the thumb member transversely of the hand, as indicated

by the arrows in the drawings, and to resist motion in an opposite direction.

On the opposite side of the middle finger member from the thumb member is provided ring and little finger members 23 and 24 respectively, which are of unitary and rigid structure curved as shown and mounted to swing from gripping position corresponding to the position of the index 10 and middle fingers to inoperative position against the palm of the hand. These ring and little finger members are provided with shoulders 25 and 26 which coöperate with corresponding shoulders on the adjacent 15 portion of the hand proper to limit the outward swing of the finger members to gripping position, shown in Fig. 1.

In practice it is to be noted that when the parts of the hand are positioned as shown in 20 Fig. 1, it may be utilized to perform any gripping function such as or analogous to carrying a suit-case or other baggage or carrying a bucket or like receptacle. When employed for this purpose it is to be noted 25 that the handle or part of the article gripped is supported by the finger members and is primarily retained in supported position by the curve of said finger members. If, however, the thumb member is arranged as 30 shown in Fig. 1, that is bearing against the index finger, it serves to positively confine the handle member in position on the fingers, and thereby preclude any possibility of displacement.

If it is desired to employ a hook or hook line grip the ring and little finger members are allowed to swing inwardly toward the palm of the hand. The thumb member is pulled away from the index finger member 40 until sufficient clearness is provided to permit of the outer phalanx being swung about the pivot 17, which allows the thumb member to pass the index finger member and then engage the ring and little finger members to 45 urge them against the palm of the hand and maintain them in this position. The index and middle finger members then constitute a hook or hook-like grip to be utilized as desired.

An important feature of my invention in practice is the relation of the index finger to the middle finger and the supplemental action of the thumb member to this relation. It is to be noted that the index finger member 55 is normally pressed against the middle finger member by the action of the spring 9, but it may be swung away from the middle finger member as by a pull on the cord 12. The motion in the event of a pull on the cord 60 12 is about an axis extending perpendicularly through the hand from the palm to the back thereof. After the index finger member has been pulled away from the middle finger member, any object such as a pencil, a 65 newspaper, the rein of a horse harness or the

like may be placed between the index and middle fingers and upon release of the pull will be effectively clasped therein. If the thumb is made to assume the position shown in Fig. 1 it will supplement the action of 70 the spring 9 and consequently enhance the clasping action.

The features of construction, operation and arrangement of parts permit of many other usages and advantages too numerous to 75 mention.

I claim:—

1. An artificial hand comprising a hand member, a middle finger member rigid therewith, an index finger member pivotally mounted on said hand to swing toward and away from said middle finger member on an axis extending perpendicularly through said hand member from the palm to the back thereof, spring means urging said index finger against said middle finger, ring and little finger members mounted for swinging movement from gripping to inoperative positions, and a thumb member mounted to swing transversely of said hand and having a pivoted end portion and spring means for urging said thumb member transversely of 80 said hand.

2. An artificial hand comprising a hand member, a middle finger member rigid therewith, an index finger member pivotally mounted on said hand member to swing toward and away from said middle finger member on an axis extending perpendicularly through said hand member from the 90 palm to the back thereof, spring means urging said index finger against said middle finger member, and a spring actuated thumb member adapted to be brought to bear against the outer side of said index finger 95 member to supplement the action of said spring means.

3. An artificial hand comprising a hand member, a middle finger member rigid therewith, an index finger member pivotally mounted on said hand member, to swing toward and away from said middle finger member on an axis extending perpendicularly through said hand member from the palm to the back thereof, and spring means 100 urging the said index finger against said middle finger, all as and for the purposes set forth.

4. An artificial hand comprising a hollow hand member, a middle finger member rigid therewith, an index finger member mounted on said hand to swing toward and away from said middle finger on an axis extending perpendicularly through said hand from the palm to the back thereof, said index finger member having an inner portion extending into the interior of said hand member beyond the pivot point of said finger and spring means abutting against the interior wall of said hand member and bearing 115 120 125 130

against said inner portion of said index finger to urge said finger against said middle finger.

5. An artificial hand comprising a hollow hand member, a middle finger member rigid therewith, an index finger member mounted on said hand member to swing toward and away from said middle finger member on an axis extending perpendicularly through said 10 hand member from the palm to the back thereof, said index finger member having an inner portion extending into the interior of said hand member beyond the pivot point of said finger, a blade spring having one end secured to the interior wall of said hand member, its intermediate portion bowed and its other end bearing against the inner portion of said index finger to urge said index finger against said middle finger member, all 15 as and for the purposes set forth.

20 6. An artificial hand including a hand member, middle and index finger members, ring and little finger members mounted for

swinging movement about an axis extending transversely of the palm of the hand and at 25 right angles to the median line of the hand from gripping to inoperative positions and a spring urger thumb member adapted bearing against the top side of said ring and middle finger members to maintain said ring 30 and little fingers in inoperative position.

7. An artificial hand comprising a hand member, a middle finger member rigid therewith, an index finger member pivotally mounted on said hand member to swing 35 toward and away from said middle finger member on an axis extending perpendicularly through said hand member from the palm to the back thereof, spring means urging said index finger member against said 40 middle finger member, and means for swinging said index finger member away from said middle finger member against the action of said spring means, all as and for the purposes set forth.

ROBERT FRANCIS ARMSTRONG.
